George W. Kamin, Arcadia, Calif., assignor to Pan-Pacific Manufacturing Corp., Los Angeles, Calif., a corporation of California

Filed Feb. 1, 1960, Ser. No. 59,226

Term of patent 3½ years

(Cl. D81—25)

I claim:

The ornamental design for a border frame for oven doors substantially as shown.
